GLOBE DIAL FIXTURE

Reinhold H. Schulz, Detroit, Mich.

Application January 5, 1933, Serial No. 650,270

2 Claims. (Cl. 90—59)

My invention relates to a globe dial fixture, and particularly to such a fixture for use on tool machines and other instruments for adjustably supporting work-holders, lay-out plates, etc.

It is an object of my invention to provide a globe dial with a top bearing surface and a bearing bolt for permitting quick and accurate exchange of work-holders such as machine plates, vises, tablets and other fixtures.

The globe surface is provided with vertical and horizontal markings similar to parallels meridians which markings serve as a dial so that work supported by the fixture can be easily and quickly adjusted to any desired vertical or horizontal angle.

15 I prefer to provide an annular supporting bearing contacting with an area of the globe surface 15° in width; also I prefer to make this contact area start at the equator of the globe and extend upward 15°. Therefore, for ease in reading and operating the fixture, the zero point on the dial is displaced 15° above the equator of the globe and cooperates with the top edge of the bearing which serves as a pointer in adjusting the globe dial.

20 25 As the globe dial has a wide range of adjustment, both vertically and horizontally, work once set up on my fixture may be finished to any desired angle without the necessity of a second set up.

30 It is a further object of my invention to provide a clamping member for the globe dial operative to fasten or release the globe by only an eighth turn of the clamping nut.

35 It is a further object of my invention to provide a press piece for locking the globe in the desired position and a resilient member for maintaining sufficient pressure on the press piece when unlocked that the globe dial will not fall over or out of adjustment because of its own weight.

40 45 Other objects and advantages will be apparent from the following detailed description taken in conjunction with the accompanying drawing showing a preferred embodiment of my invention.

The apparatus according to my invention comprises a globe dial 1 having horizontal and vertical dial markings. The globe dial 1 is mounted in a housing 4 having a substantially cylindrical opening extending upwardly therethrough and terminating in a restricted portion having the same radius as the globe, providing a bearing surface for engaging the globe dial. The restricted bearing portion is of sufficient length to cover 15° of the globe surface upward from the equator of the globe.

15° above the globe center and coinciding with the upper edge of the bearing surface. These markings extend 45° above and below the zero line.

60 The globe 1 is provided with a bearing bolt 5 adapted to carry suitable fixtures 6 such as machine plates, vises, jigs, etc. A suitable fastening nut 7 is provided for securing the fixtures 6 on the bolt 5.

The globe 1 is retained in the housing 4 by a press piece 2 having an annular bearing surface conforming to the surface of the globe 1.

65 The press piece 2 and the globe 1 are retained in the housing 4 by a suitable closure member 3. Preferably the press piece 2 has a stem extending through the closure 3 and keyed thereto in such a manner that it is free to move to or from the globe but is held against rotation.

70 75 The stem of the press piece 2 is provided with threads with which cooperate a clamping nut 8. The threads of the clamping members have a steep pitch so that an eighth turn of nut 8 will move press piece 2 to or from clamping position.

80 Resilient means such as coil springs 9 are provided between the press piece 2 and closure 3 so that the press piece 2 is constantly engaged with globe 1. Preferably, the springs 9 exert sufficient force to prevent the globe from turning of its own weight when the clamping members 85 are in the open position.

85 The housing 4 has an opening A for a suitable operating extension for nut 8.

90 95 The bearing in press piece 2 ends in a sharp edge which acts to remove all foreign material adhering to the surface of the globe 1, thus insuring a perfect, accurate seat between the globe 1 and press piece 2. A suitable groove 10 is provided in the press piece for receiving all dirt removed by the cleaning edge.

100 105 While I have shown and described a specific embodiment of my device, it will be apparent to those skilled in the art that changes and modifications can be made without departing from the true spirit of my invention.

I claim:

1. A globe dial fixture comprising a holder having a substantially cylindrical passage therethrough, a restricted portion in said passage, an annular bearing surface in said restricted portion, a globe dial received in said passage and seating on said annular bearing, a press-piece for pressing said dial against said bearing, an annular bearing on said press-piece, a closure for said passage, said closure having an opening 110

therein, a stem on said press-piece extending through said opening, means for preventing relative rotation between said closure and said stem, a member in threaded engagement with said stem for controlling said press-piece and resilient means for maintaining said press-piece in contact with said dial.

2. A globe dial fixture comprising a base member, a globe dial received in said base member and having a portion extending thereabove, an annular bearing cooperating with said globe dial, said bearing being of too small a size to permit

the globe to pass therethrough, a press piece in said base for pressing the globe into locking engagement with said bearing, a threaded extension on said press piece, a nut threadably engaged with said extension for controlling the press piece, the threads on said nut and press piece being of such a pitch that an eighth turn of the nut operates the press piece, and means on said press piece for removing dirt from the surface of the globe cooperating with the bearing in the press piece.

REINHOLD H. SCHULZ.
